UNITED STATES PATENT OFFICE

146,430

DESIGN FOR AN ALPHABET

Andrew G. Giegold, Jr., Mount Vernon, N. Y.

Application March 2, 1946, Serial No. 127,049

Term of patent 7 years

(Cl. D64—12)

To all whom it may concern:

Be it known that I, Andrew G. Giegold, Jr., a citizen of the United States, residing at Mount Vernon, in the county of Westchester and State of New York, have invented a new, original, and ornamental Design for an Alphabet, of which the following is a specification, reference being had to the accompanying drawings, forming part thereof.

Figs. 1 and 2 are perspective views of an alphabet, showing my new design.

I claim:

The ornamental design for an alphabet, as shown.

ANDREW G. GIEGOLD, JR.
